UNITED STATES PATENT OFFICE.

LOUIS ALFANO, OF SOUTHBURG, CONNECTICUT, ASSIGNOR OF ONE-HALF TO FRANK GALIETTI, OF SOUTHBURG, CONNECTICUT.

DEVICE FOR PRINTING DIAGRAMS FOR TAILORS' PATTERNS.

1,130,653.

Specification of Letters Patent.

Patented Mar. 2, 1915.

Application filed March 16, 1914, Serial No. 825,105. Renewed December 17, 1914. Serial No. 877,807.

To all whom it may concern:

Be it known that I, LOUIS ALFANO, a subject of the King of Italy, residing at Southbury, in the county of Hartford and State 5 of Connecticut, have invented a new and useful Improvement in Devices for Printing Diagrams for Tailors' Patterns; and I do hereby declare the following, when taken in connection with the accompanying drawings, and the characters of reference marked thereon, to be a full, clear, and exact description of the same, and which said drawings constitute part of this application, and represent in—

15 Figure 1 a top or plan view of a device for printing tailors' diagrams constructed in accordance with my invention. Fig. 2 an underside view of the same. Fig. 3 a sectional view on the line *a—b* of Fig. 1. Fig. 20 4 a sectional view on the line *c—d* of Fig. 1. Fig. 5 a broken sectional view indicating means for locking the operating lever. Fig. 6 a broken sectional view on an enlarged scale showing the end of one of the markers 25 as indicated, with the frame. Fig. 7 indicates a diagram which may be printed with this device.

This invention relates to an improvement in devices for printing diagrams for tailors' 30 patterns. In laying out patterns for coats and vests, it is desirable to use a diagram consisting of horizontal and substantially vertical lines, the vertical lines varying with the different sizes to be cut, these vertical 35 lines, however, all having a relative position corresponding to certain fixed sizes.

The object of this invention is to provide a device by which these diagram lines may be printed, and the invention consists in the 40 construction hereinafter described and particularly recited in the claims.

In carrying out my invention, I employ a frame 2 of suitable size the under face of which is provided with a strip or top line 45 3 and preferably with certain gages and scales 4, 5 and 6. Within the frame are a series of vertical markers 7, 8, 9, 10 and 11, the marker 11 being curved. These several markers are connected with a lever 12 which 50 is pivoted at one end of the frame and exposed through the outer face thereof, the outer end of the lever being adapted to be engaged with a segmental scale 13 with which it may be locked by a pin 14 entering

perforations 15 in the scale. The connection 55 with the lever is made through coupling-pieces 16 a separate piece being employed for each of the vertical markers. In addition the curved marker 11 is coupled at its upper end by a link 17 with a slide 18 moved 60 by the lever 12. To lay out a diagram as indicated in Fig. 7, the lever 12 will be turned, for instance, as shown in Fig. 1, to 38, which will give the dimensions for a coat or vest of 38 bust measure. This movement of the 65 lever has moved the vertical markers to the proper position. The edges of these markers are provided with strips 19 like the edge 3 of rubber or other suitable material which will hold ink which may be applied to them 70 by a roller, or the device may be pressed upon a suitable pad whereby the edges of the vertical markers and the edge of the frame may receive a coating of ink. The device is then placed upon a sheet of pattern paper and sufficient pressure placed upon it to imprint upon the pattern paper the solid lines indicated in Fig. 7 and from which a pattern may be completed, the scales 4, 5 and 6 giving the pattern maker 80 the points from which to strike the necessary lines. I thus provide a device which will give an accurate diagram for a large range of sizes.

I claim:—

1. A device for printing tailors' diagrams comprising a frame provided with a printing edge, a series of vertical markers having printing edges slidably mounted in said frame, a lever pivoted in the frame, and coupling-pieces between the lever and the several vertical markers.

2. A device for printing tailors' diagrams comprising a frame having a printing edge and printing scales, a series of vertical 95 markers mounted in the frame and each provided with a printing edge, a lever coupled with the frame and connected with the several markers, and a segmental scale on the frame with which the outer end of the 100 lever may be locked.

In testimony whereof, I have signed this specification in the presence of two subscribing witnesses.

LOUIS ALFANO.
